CLAIM

The ornamental design for an implement for activating
and deactivating a telephone hook switch, substantially
as shown and described.

DESCRIPTION

FIG. 1 is a front, top and right side perspective view of
an implement for activating and deactivating a tele-
phone hook switch showing my new design.

FIG. 2 is a top plan view thereof;

FIG. 3 is a left side elevational view thereof;

FIG. 4 is a rear elevational view thereof; and

FIG. 5 is a bottom plan view thereof.
